UNITED STATES PATENT OFFICE.

JOHN B. TIMBERLAKE, OF JACKSON, MICHIGAN.

DISPLAY-RACK.

No. 874,917.

Specification of Letters Patent.

Patented Dec. 24, 1907.

Application filed December 23, 1903. Serial No. 186,360.

To all whom it may concern:

Be it known that I, JOHN B. TIMBERLAKE, a citizen of the United States, residing at Jackson, in the county of Jackson and State of Michigan, have invented certain new and useful Improvements in Display-Racks, of which the following is a specification, reference being had therein to the accompanying drawing.

10 This invention relates to improvements in display racks.

It has for its object to provide a rack of simple construction which may be employed for displaying articles of various kinds.

15 Figure 1 is a perspective view of a display rack embodying my improvements, showing in dotted lines a plate supported thereby. Fig. 2 is a perspective view of parts of the device shown in Fig. 1 in the course of construction. 20 Fig. 3 is a view of several parts of the device in course of construction. Fig. 4 is a perspective view of a modified form of the device. Fig. 5 is still another modification.

The rack or easel essentially consists of 25 two parts, namely, the base or stand 1 and the vertical frame or rest 2 carried thereby and adapted to hold the article to be displayed upon the said stand in a relatively upright position. This vertical support or 30 rest 2 is preferably made of a single piece of wire or strand of twisted wire, bent to form the uprights 3—3 and the connecting part 4. At the lower ends of the uprights 3 the ends 3'—3' of the wire or strands are bent at substantially right angles to said uprights. 35 The base or supporting frame 1 is likewise formed of a single piece of wire or strand of twisted wire bent to form the loops 5—5 at either side of the rear of the frame and which 40 are connected by the part 6. From the said loops the wires extend forward as indicated at 7—7. Before securing the upright frame or rest to the base, I may place on the upwardly extending portions thereof a rubber 45 tubing or sheathing 8. As shown in Fig. 3 the ends 3'—3' of the wire which forms the upright part of the frame and the parts 7—7 of the base may then be twisted together as at 9—9. When desired, pieces of rubber 50 tubing or sheathing 10—10 may then be forced over the twisted portions 9—9 as shown in Fig. 4. The ends 11—11 of the

piece of wire of which the base is formed may then be bent upwardly as indicated at 12—12 to form shoulders against which the 55 lower edge of the plate or article to be displayed may abut, and the ends may then be bent downwardly and coiled as shown at 13—13 to form the forward points of support for the base. It will be understood that 60 I do not limit myself to the use of rubber tubing for providing a resilient supporting surface for the plates or articles to be displayed, as any suitable material possessing the desired resiliency may be used without 65 departing from the spirit of my invention. A coating of rubber could be applied to the easel or rack after it is formed and caused to harden thereon in any well known manner.

70 In the modification shown in Fig. 4 the resilient cover for the base and the uprights has been dispensed with. There is sufficient wire in each of the horizontally disposed ends 3'—3' of the vertically disposed frame 75 or rest 2 to provide for the necessary twisting of said wire with the wire 7—7 of the base and then to be bent upwardly and looped as indicated at 3a—3a. In this construction the ends of the wires 7—7 of the 80 base after being twisted together with the wires 3'—3' are bent downwardly and looped as indicated at 13—13 to form the front supports for the base.

85 In Fig. 5 is shown an easel for supporting an album. In this construction after the ends 3'—3' of the wires which form the upright frame and the wire 7—7 of the base have been wound together, the latter are bent downwardly and coiled at 13—13 to form the front 90 supports for the easel. Numerous modifications will suggest themselves according to the nature of the article which the easel is to support. It will be noted that only two pieces of wire or strands of twisted wire are necessary to 95 form any of the desired constructions. However, I do not limit myself to the use of two pieces of wire, as an easel embodying my invention may be made in which several wires are used, but in which the essential features 100 of my invention are present.

It will be noted that the cross tie piece 6 between the feet 5—5 is arranged above the horizontal plane of the points of contact be-

tween the feet 5—5 and the surface upon which they rest. This insures that in case the frame is sprung or the feet in any wise bent in reference to each other that the tie 5 piece between them will not contact with the supporting surface for the rack and make a wabbly structure. The cross tie piece 6 that connects the two substantially horizontal portions of the base operates to strengthen 10 the frame and hold the feet in proper relation to each other.

While I have referred to the sheathing or protecting device incasing a portion of the frame as being composed of rubber, it will be 15 noted that I do not limit myself thereby to the use of that material alone. It is particularly suitable because of the resilient surface which it provides, but it will be noted that any non-metallic material may be substituted which will serve to protect fragile 20 dishes or like articles from being chipped or nicked by the rack. Furthermore this protecting material may be dispensed with on the upright frame when desired and sim- 25 ply used upon that portion of the base with which the articles to be displayed contact. Again the protecting material may be applied to all portions of the easel frame when desired, without departing from the spirit of 30 the invention.

In each of the several forms of my invention illustrated in the accompanying drawings there is found a base having substantially horizontal members, indicated by 7, 7, that 35 are held above the surface of the support for the rack by feet formed at the ends of the base. Extending upward from the horizontal members of this base is a rest 2 against which the article leans. The rest and base 40 are rigidly united so that there is no danger of one moving relative to the other, even though an article of considerable weight be supported and bear heavily upon the rest. By giving to the horizontal members of the 45 base considerable extension between the attachment of the upright rest 2 therewith and the forward feet of the base a support is produced that will accommodate a wide variety of articles, and accommodate them in different 50 positions. Thus if a shallow plate, such as indicated by dotted lines in Fig. 1, be supported it can be held nearly upright or given a considerable inclination. This same rack is equally adapted to hold a deep dish, such 55 as a bowl, or an article like an album, as indicated in Fig. 5. By inter-twisting the extensions 3' of the upright rest with the horizontal members of the base, the latter is strengthened, and it is particularly desirable 60 that this strengthening should be in front of the rest, that is to say, those portions of the horizontal members upon which the edge of

the article to be displayed rests are strength- 65 ened. This enables a relatively light wire to be employed in forming the rack and at the same time gives sufficient strength and rigidity to those parts of the base with which the article directly engages to prevent sagging thereof, even when a heavy dish or other article is placed upon the rack.

I do not herein make claim to a rubber 70 covered easel, claims of that nature being presented in application Serial Number 320,851, filed June 8, 1906.

What I claim is—

1. A display rack comprising a base formed of wire and having horizontal portions 7 upon which the edge of the article may rest formed with feet at each end and having a cross connecting piece, and an 80 upright rest against which the article may lean formed of a piece of wire separate from the base and having its ends inter-twisted with the horizontal portions of the base, substantially as set forth.

2. A display rack comprising a base formed of a single piece of wire and having approximately horizontal members with feet at their opposite ends, and an upright 90 rest 2 formed of another piece of wire having its ends extended forward of the rest and inter-twisted with the horizontal members of the base, substantially as set forth.

3. A display rack formed of wire and comprising horizontal portions 7 with feet at 95 their ends, an upright rest against which the article displayed may lean, and shoulders arranged in front of the rest and rising above the horizontal portions 7 of the base to serve as abutments for the article, the ends of the 100 rest being inter-twisted with the horizontal portions of the base between the upright rest and the said shoulders, substantially as set forth.

4. A display rack formed of a single piece 105 of wire bent to form horizontal portions 7 and having feet at the ends thereof, and an upright rest 2 formed of another piece of wire having its ends extended to one side of the upright portion of the rest and there in- 110 ter-twisted with the horizontal portions of the base between the upright and the feet at one end of the base, substantially as set forth.

5. A display rack comprising a base 1 115 formed of a single piece of wire having ap- proximately horizontal supporting members and rests or feet, and an upright rest 2 formed of another piece of wire having its ends inter-twisted with the horizontal mem- 120 bers of the base, and rubber sheathings cov- ering the inter-twisted portions of the base and rest, substantially as set forth.

6. In a display rack, the combination of a

base having horizontally arranged pieces 7, 7, supported at their ends by feet formed integral therewith, an upright frame 2 formed of wire and having side pieces 3, 3, the lower 5 end of each of said pieces being twisted about one of the horizontal pieces 7, 7, of the base and sheathings of rubber incasing the unions between the base and the upright frame and

also the wire of the upright frame, substantially as set forth.

In testimony whereof I affix my signature 10 in presence of two witnesses.

JOHN B. TIMBERLAKE.
